(57) **CLAIM**

The ornamental design for wireless audio headphones with magnetic ear cushions according to my invention, as shown and described herein.

DESCRIPTION

FIG. 1 is a perspective view the ornamental design for a first embodiment of wireless audio headphones with magnetic ear cushions according to my invention;

FIG. 2 is a front view of the ornamental design for the first embodiment of wireless audio headphones with magnetic ear cushions according to my invention;

FIG. 3 is a rear view of the ornamental design for the first embodiment of wireless audio headphones with magnetic ear cushions according to my invention;

FIG. 4 is a side view of the ornamental design for the first embodiment of wireless audio headphones with magnetic ear cushions according to my invention;

FIG. 5 is an opposing side view of the ornamental design for the first embodiment of wireless audio headphones with magnetic ear cushions according to my invention;

FIG. 6 is a bottom view of the ornamental design for the first embodiment of wireless audio headphones with magnetic ear cushions according to my invention;

FIG. 7 is a top view of the ornamental design for the first embodiment of wireless audio headphones with magnetic ear cushions according to my invention;

FIG. 8 is a perspective view of the ornamental design for the first embodiment of wireless audio headphones with magnetic ear cushions according to my invention, wherein the magnetic ear cushions are shown detached from the headband portion;

FIG. 9 is a front view of the ornamental design for the first embodiment of wireless audio headphones with magnetic ear cushions according to my invention, wherein the magnetic ear cushions are shown detached from the headband portion;

FIG. 10 is a rear view of the ornamental design for the first embodiment of wireless audio headphones with magnetic ear cushions according to my invention, wherein the magnetic ear cushions are shown detached from the headband portion;

FIG. 11 is a side view of the ornamental design for the first embodiment of wireless audio headphones with magnetic ear cushions according to my invention, wherein the magnetic ear cushions are shown detached from the headband portion, wherein the magnetic ear cushions are shown detached from the headband portion;

FIG. 12 is an opposing side view of the ornamental design for the first embodiment of wireless audio headphones with

(Continued)

magnetic ear cushions according to my invention, wherein the magnetic ear cushions are shown detached from the headband portion;

FIG. 13 is a bottom view of the ornamental design for the first embodiment of wireless audio headphones with magnetic ear cushions according to my invention, wherein the magnetic ear cushions are shown detached from the headband portion;

FIG. 14 is a top view of the ornamental design for the first embodiment of wireless audio headphones with magnetic ear cushions according to my invention, wherein the magnetic ear cushions are shown detached from the headband portion;

FIG. 15 is a perspective view the ornamental design for a second embodiment of wireless audio headphones with magnetic ear cushions according to my invention;

FIG. 16 is a front view of the ornamental design for the second embodiment of wireless audio headphones with magnetic ear cushions according to my invention;

FIG. 17 is a rear view of the ornamental design for the second embodiment of wireless audio headphones with magnetic ear cushions according to my invention;

FIG. 18 is a side view of the ornamental design for the second embodiment of wireless audio headphones with magnetic ear cushions according to my invention;

FIG. 19 is an opposing side view of the ornamental design for the second embodiment of wireless audio headphones with magnetic ear cushions according to my invention;

FIG. 20 is a bottom view of the ornamental design for the second embodiment of wireless audio headphones with magnetic ear cushions according to my invention;

FIG. 21 is a top view of the ornamental design for the second embodiment of wireless audio headphones with magnetic ear cushions according to my invention;

FIG. 22 is a perspective view of the ornamental design for the second embodiment of wireless audio headphones with magnetic ear cushions according to my invention, wherein the magnetic ear cushions are shown detached from the headband portion;

FIG. 23 is a front view of the ornamental design for the second embodiment of wireless audio headphones with magnetic ear cushions according to my invention, wherein the magnetic ear cushions are shown detached from the headband portion;

FIG. 24 is a rear view of the ornamental design for the second embodiment of wireless audio headphones with magnetic ear cushions according to my invention, wherein the magnetic ear cushions are shown detached from the headband portion;

FIG. 25 is a side view of the ornamental design for the second embodiment of wireless audio headphones with magnetic ear cushions according to my invention, wherein the magnetic ear cushions are shown detached from the headband portion, wherein the magnetic ear cushions are shown detached from the headband portion;

FIG. 26 is an opposing side view of the ornamental design for the second embodiment of wireless audio headphones with magnetic ear cushions according to my invention, wherein the magnetic ear cushions are shown detached from the headband portion;

FIG. 27 is a bottom view of the ornamental design for the second embodiment of wireless audio headphones with magnetic ear cushions according to my invention, wherein the magnetic ear cushions are shown detached from the headband portion; and,

FIG. 28 is a top view of the ornamental design for the second embodiment of wireless audio headphones with magnetic ear cushions according to my invention, wherein the magnetic ear cushions are shown detached from the headband portion.

The broken lines are illustrative of environmental structure only and form no part of the claimed design.
